UNITED STATES PATENT OFFICE.

FRED L. MANNY, OF BENTON HARBOR, MICHIGAN, ASSIGNOR TO BAKER-VAWTER COMPANY, OF BENTON HARBOR, MICHIGAN, A CORPORATION OF MICHIGAN.

LOCKING MECHANISM FOR POST-BINDERS.

1,331,516.

Specification of Letters Patent.

Patented Feb. 24, 1920.

Application filed October 2, 1918. Serial No. 256,495.

To all whom it may concern:

Be it known that I, FRED L. MANNY, a citizen of the United States, residing at Benton Harbor, in the county of Berrien 5 and State of Michigan, have invented certain new and useful Improvements in Locking Mechanism for Post-Binders, of which the following is a specification.

My invention pertains to what are known 10 as loose leaf binders designed to hold a body of separate perforated sheets of paper in the form of ledgers or other account books of the well known type in which one of the sides or covers is provided with a hinged 15 clamping bar or iron equipped with a series of posts arranged to engage the perforations of the sheets and the other cover is provided with a similar hinged clamping bar equipped with means for locking it in 20 any desired position of adjustment on said posts.

The object of my invention is to provide a simple and reliable locking mechanism for the purpose mentioned which shall render it 25 superior in some respects to any prior mechanism for the same purpose known to me and which shall be efficient and desirable for the use in view. Among the advantages exhibited by my novel locking device 30 it may be mentioned that the same mechanism with the same locking bolt may be used with clamping plates or irons varying in size, and this bolt will lock on any desired number of posts without modification 35 of construction. My invention consists in the construction, arrangement and organization of coöoperating parts making up my novel locking mechanism, the essential elements of which are recited in the appended 40 claims, it being understood however, that modifications in details of the specific structure described may be made within the scope of such claims and without departing from the spirit of my invention.

45 Of the drawings Figure 1 is a plan view of the hollow clamping bar of the detachable cover of a binder, parts of the bar being broken away to show the mechanism housed therein; Fig. 2 is a vertical longitudinal section of the same on the line 2—2 of Fig. 1; Fig. 3 is a cross-section on the line 3—3 of Fig. 1; Fig. 4 is a perspective of the locking bolt detached; Fig. 5 is a perspective of a spacing and supporting bracket en-

gaging the operating screw; and Fig. 6 a 55 cross-section on the line 6—6 of Fig. 1.

The same reference characters indicate the same parts on all the figures of the drawing.

While the specific construction of the 60 hinged clamping bar 1 carrying the binder posts 2 of the lower cover 3 is immaterial, so far as my present invention is concerned, it may conveniently be constructed, as shown, 65 in the form of a hollow sheet metal shell, and the posts may be made sectional in order that by the use of intermediate sections they may be extended to any length desired. The clamping bar or iron 4 of the detachable cover is a hollow composite 70 structure consisting of an outer sheet metal plate 5 formed with recurved flanges 5^a at its opposite sides arranged to embrace the outwardly bent portions 6^a of coöoperating flanges on an inner plate 6. The plates 5 75 and 6 are formed with registering perforations arranged to receive the binder posts 2, which pass though the chamber between the plates adjacent one side thereof, leaving a space on the other side of posts in which 80 is arranged a locking bolt 7. At a point intermediate two of the posts this bolt is formed with a bent portion 7^a constituting a short crank, the outer surface or end of this crank having a short inward curve 85 which is provided with threads forming a segmental worm gear arranged to engage an operating screw to be hereinafter described. This bent portion of the bolt is cut away 90 longitudinally as shown to permit a limited 95 degree of oscillation to be imparted to the bolt, and the side of the bolt next the posts 2 is cut away to form a flat face which slid- 100 105 ily engages the posts when parallel with them.

The lock bolt is rotated to cause the flat face thereof to grip the posts and thereby lock them to the clamping bar structure by means of a turning key 9 rotatably mounted in the members of the clamping bar and 100 equipped with a screw member 10. For convenience in manufacture and assembling the parts the key is formed with a square shank 10^a which engages a square socket in said screw member, such member being secured thereto by means of a headed retaining screw 12. The thrust of this screw member 10 is received by the thrust washer

13 interposed between it and the outer plate 5 of the clamping bar.

For the purpose of strengthening and better supporting the screw member I have 5 provided a bearing block formed with bottom flanges welded upon the inner plate 5 of the clamping bar and a semicylindrical bearing portion 15 engaging the screw member and interposed between it and the adjacent side flange of the inner plate 6 of the clamping bar.

As shown, the screw member 10 is a left-handed screw and when the face of the locking bolt is parallel with the posts to permit sliding adjustment of the clamping bar structure thereon, the bent or crank portion of the bolt is in uppermost position. It is obvious that with this arrangement and construction of the parts the bend 7^a will be depressed through the action of the screw and worm gear by turning the key to right, and the bolt will be rotated to cause its flat face to impinge against the binder posts and lock the clamping bar upon them.

25 I claim:

1. In a loose leaf binder having one cover equipped with binder posts and the other cover equipped with an orificed clamping bar arranged to engage said posts, locking mechanism comprising a rotatable bolt mounted longitudinally on the clamping bar and formed with an engaging face arranged to impinge against said posts when the bolt is rotated, a segmental worm gear on said bolt, and a screw coöperating with said worm gear to rotate the bolt.

2. In a loose leaf binder having one cover equipped with binder posts and the other cover equipped with an orificed clamping bar 40 arranged to engage said posts, locking mechanism comprising a rotatable bolt mounted longitudinally on the clamping bar

and formed with an engaging face arranged to impinge against said posts when the bolt is rotated, said bolt being formed with a 45 bend and the bent portion formed with threads to constitute a segmental worm gear, and a screw coöperating with said worm gear to rotate the bolt.

3. In a loose leaf binder having one cover 50 equipped with binder posts and the other cover equipped with a hollow orificed clamping bar arranged to engage said posts, locking mechanism comprising a rotatable bolt housed within said bar and formed with an 55 engaging face arranged to impinge against said posts when the bolt is rotated, a manually operable key journaled in the opposite walls of said clamping bar, and a worm-gear connection intermediate said key and bolt. 60

4. In a loose leaf binder of the character described, locking mechanism according to claim 3 in which the operating key is formed with a polygonal shaft arranged to engage the worm member of the worm gear connection. 65

5. In a loose leaf binder having one cover equipped with binder posts and the other cover equipped with an orificed clamping bar arranged to engage said posts, locking 70 mechanism comprising a rotatable bolt mounted longitudinally on the clamping bar and formed with an engaging face arranged to impinge against said posts when the bolt is rotated, said bolt being provided with a 75 segmental worm gear, an operating key journaled in the opposite walls of said clamping bar and a screw carried thereby arranged to coöperate with said worm gear, and a supporting block formed with a semi- 80 cylindrical bearing face engaging said screw and arranged between such screw and the adjacent wall of the clamping bar. 85

FRED L. MANNY.
